UNITED STATES PATENT OFFICE

96,344

DESIGN FOR A VELOCIPED

Otto W. Siebert, Gardner, Mass., assignor to O.
W. Siebert Company, Gardner, Mass., a corpo-
ration of Massachusetts

Application March 19, 1935, Serial No. 55,947

Term of patent 7 years

To all whom it may concern:

Be it known that I, Otto W. Siebert, a citizen of the United States, residing at Gardner, in the county of Worcester and State of Massachusetts, have invented a new, original, and ornamental Design for Velocipede, of which the following is a specification, reference being had to the accompanying drawing forming part thereof.

Fig. 1 is a rear view of a velocipede showing my new design;

Fig. 2 is a partial plan view, and

Fig. 3 is a sectional side elevation taken on the line 3—3 in Fig. 2.

The dominant feature of the invention resides

in the step plate shown in solid lines which is substantially rectangular in top plan and which has a short and abruptly inclined front portion, a long and gradually inclined rear portion, a curved portion joining said front and rear portions and tangential thereto, horizontal lower end edges and segmental end portions of relatively short and substantially equal radii joining said inclined portions to said lower end edges and tangential thereto.

I claim:

The ornamental design for a velocipede, as shown and described.

OTTO W. SEIBERT.
